UNITED STATES PATENT OFFICE.

GEORGE O. P. KUNICKE, OF PLAINFIELD, NEW JERSEY.

MACHINE FOR OPERATING ON WOOD STRIPS.

1,355,749.

Specification of Letters Patent.

Patented Oct. 12, 1920.

Application filed May 27, 1920. Serial No. 384,679.

To all whom it may concern:

Be it known that I, GEORGE O. P. KUNICKE, a citizen of Germany, and a resident of Plainfield, in the county of Union and State of New Jersey, have invented a new and Improved Machine for Operating on Wood Strips, of which the following is a description.

My invention relates more particularly to 10 a machine for performing certain operations on the wood strips entering into the pneumatics of player pianos, two of said strips being employed in the pneumatic. At one end where the strips converge when 15 in use, the strips are formed at the opposed side edges with shallow grooves to accommodate the material of the bellows. Also, in one of said strips at the back two blind punctures or depressions are produced to 20 receive the screws of the operating arm of the pneumatic action. The punctures are produced to prevent the screws from splitting the strip and for a similar reason the punctures are out of longitudinal alinement.

25 My invention has for its object to produce a machine to automatically groove and puncture the strips.

Reference is to be had to the accompanying 30 drawings forming a part of this specification, it being understood that the drawings are merely illustrative of one example of the invention.

Figure 1 is a side elevation of a machine 35 embodying my invention;

Fig. 2 is a longitudinal vertical section in a plane corresponding with the line 2—2, Fig. 3;

Fig. 3 is a plan view of the bed and the 40 parts directly associated therewith, the super-structure being omitted except one vertical end with the thrust block thereon and the holder for the stack of strips, said holder being shown in section on a line 45 corresponding with the line 3—3, Fig. 13 and the similar line 3—3, Fig. 6, certain features of the removable super-structure particularly relating to the adjustable side of the stack holder being indicated by dotted lines;

Fig. 4 is a detail in horizontal section on the line 4—4, Fig. 2;

Fig. 5 is a detail in horizontal section on the line 5—5, Fig. 2;

55 Fig. 6 is an end view, a portion of the

machine at the top being broken away and others in section;

Fig. 7 is a plan view partly broken away and in section of the vertically reciprocating puncturing head;

60

Fig. 8 is a transverse vertical section on the line 8—8, Fig. 7;

Fig. 9 is a detail in end view looking in the direction of the arrow 9 in Fig. 3;

Fig. 10 is a plan view of the parts shown 65 in Fig. 9;

Fig. 11 is a transverse vertical section as indicated by the line 11—11, Fig. 2;

Fig. 12 is a transverse vertical section as indicated by the line 12—12, Fig. 2;

70

Fig. 13 is a side elevation of one end of the machine at the opposite side from Fig. 1;

Fig. 14 is a perspective view of the strip having the edge grooves and punctures formed therein by my machine.

75

In carrying out my invention in practice in accordance with the illustrated example, strips A are stacked in a holder designated generally by the numeral 15, at the side of which is a pusher plate 16 adapted to laterally reciprocate to displace the lowermost strip of the stack and move the same transversely, to dispose the strip finally in the position indicated by the letter a in Fig. 3, alongside of a longitudinal gage bar 17 disposed on the bed 18 of the machine and with one end of the strip beneath a thrust block 19 secured as by a bolt 19^a, said end of the strip and said thrust block being directly above a puncturing head 20 provided with pins 20^a and adapted to be reciprocated through a vertical opening 18^a in the bed 18. Said pins produce blind punctures a' (Fig. 14) in one face of the strip out of line with each other, adapted to receive the screws to secure the usual operating arm to 80 said pneumatic.

85

When the strip is positioned at the dotted line position a of Fig. 3 and with one end under the thrust block 19 as stated, said strip is at the same time disposed beneath a traveling feed belt 21 disposed longitudinally of the machine above the bed thereof, to frictionally engage the top surface of said strip. Said belt runs about rollers 22^a 100 mounted in a frame 22, the forward end of which is secured by a transverse shaft 23 on which said frame is loosely mounted to be rocked in a vertical plane by means hereinafter described to permit an arriving 105

110

strip to pass beneath the belt 21. The belt 21 feeds the strip forwardly onto a second endless belt 24 traveling approximately flush with the surface of the bed 18, there 5 being a feed roller 25 for the strip above one of the rollers 24^a about which said belt 24 travels. The roller 25 feeds the strip forwardly to a pair of saws 26 on a transverse shaft or arbor 26^a for producing 10 grooves α^2 at opposite sides of the strip A in a face thereof and extending from one end a short distance longitudinally of the strip. In response to the feeding action of the roller 25 and its pressure on the strip 15 A and hence on the belt 24, said belt will travel forwardly with the strip thereby minimizing friction.

The saws 26 and roller 25 are so disposed relatively to each other and relatively to 20 the length of the strip that said strip will be held by said roller until the saws have cut the grooves, α^2 , the desired lengths after which the strip upon leaving the roller 25 will be shot forwardly by the action of the 25 saws thereon and discharged from the machine. Beyond the saws 26 I provide resilient means against which the strip is thrown by the saws, whereby to reduce the 30 speed of the discharged strip, there being shown for the purpose in the illustrated example (see Fig. 2) a plate spring 27 disposed longitudinally, said spring being returned at the under side and formed with a bent terminal 27^a secured to any suitable 35 supporting structure 27^b.

The stack holder 15 is formed with an 40 adjustable side 28 and an adjustable end 29 for varying the effective size of the box to suit strips of different sizes, the means provided for the adjustment in the illustrated example being as follows: On the side 28 (see Fig. 6) adjacent to one edge and near the bottom an adjusting screw 30 is provided extending through a slot 31 in 45 the fixed end wall of the box, said end wall being a continuation of the vertical end plate 48 secured to the machine structure above the bed 18. The plate 28 is adjustably secured at its opposite edge at the 50 top of the plate as follows: An element 36 is secured to the top of said plate 28 by a screw bolt 37 or the like and has a pin or bolt 33 above and parallel with the top edge of said plate, which pin is adapted to move 55 in a slot 34 in an arm 35 extending laterally inward from an upward extension 29^a on the end plate 29. The screw bolt 37 securing the element 36 to side plate 28 passes through a longitudinal slot 38 in said side 60 plate so that it may move in said slot and thereby the element 36 and the end plate 29 may be adjusted to conform to a strip A of given length. In a given adjusted position of the side plate 28 it is backed up 65 by angle braces 28^a, the positions of said

braces being indicated in dotted lines, Fig. 3. Said braces have longitudinal slots 28^b through which screws 28^c pass into the upper edge of the adjacent side wall 47 of the super-structure. 70

As seen best in Fig. 13 the end wall 29 is adjustably secured at its lower edge, there being a block 40 thereon receiving a transverse bolt 39 adjustable longitudinally of the machine in a slot 41 formed between the 75 under side of the bed 18 and the plate 42 fastened beneath said bed.

The gage 17 constitutes one side of a guideway for the strip in its forward movement; the opposite side of said guideway is 80 formed jointly by a fixed guide strip 45 secured by screws 46 or the like and an aligned guide strip 43 rigid with the adjustable end 29 of the stack holder which is connected therewith by an arm 44, so that said guide 85 strip member 43 will be adjusted with the adjustment of the stack holder to suit a strip of given length. The sides 47 are held by bolts 49 and 50, the latter bolt being adapted to turn in a bearing 50^a secured to the bed 90 18. The end 48 is detachably fastened to the bed by brackets 51 receiving screws 52. The super-structure is arranged to be raised from the bed 18 by swinging it about the bolt 50 as a center. In order to permit the 95 super-structure to be raised it is necessary only to unfasten the brackets 51 from the bed 18 or end 48 and remove the bolt 91 to disconnect the frame 22 from its operating arm 88, hereinafter referred to. The bed 100 18 is supported on any suitable frame 53.

The pusher plate 16 is formed with an arm 54 at the back thereof extending laterally outward formed with a slot 55 which receives a screw 56 to adjustably secure said plate to a carrier frame including a bracket 57 having a dependent flange 59 through which a bolt 58 passes into a frame member 60 to a longitudinal member 60^a of frame element 60 which is bent twice at right angles to present at one end a terminal flange 61 rigid with a transverse bar 62 to the inner end of which is connected one end of the retractile spring 63, the opposite end of which spring is suitably secured as at 64 110 to a fixed part of the machine. Said spring 63 tends to draw the pusher 16 toward the stack to feed a strip A from the bottom of the stack laterally inward toward the element 17. The frame member 60 and bar 120 62 have guided movement in any suitable members such as hangers 65, 65^a, at the under side of the bed 18. To retract the pusher plate 16 after an inward feed movement thereof, a hanger 66 is rigidly fastened at its upper end as by a pin 67 to the frame member 60 and depends therefrom. The lower end of said hanger is provided with a horizontal roller 68, the shank of which extends into the hanger and is fastened by 125 130

a set screw 69. Said roller engages a revolving cam 70 mounted on a transverse shaft 71. The arrangement is such that the turning of the cam 70 alternately moves the plate 16 outwardly and permits said plate to move inwardly under the action of the spring 63. The amplitude of movement given to the pusher plate 16 will depend on the width of the strips A to be operated upon. In practice, there will be on the bed in addition to the strip adjacent to the gage 17 one or more additional strips between the first-mentioned strip and those in the stack. The movement of the pusher plate 16 will be sufficient to successively place the strips against the gage 17 as the strips are successively moved forward by the belt 21. The gage 17 has at its outer end a transverse head 71 having a bottom plate 72 overlapping the bed 18 at the under side and said gage is adjustable transversely of the bed by reason of a bolt 73 and nut 74, said bolt passing through said gage 17 and through a slot 75 in the bed 18 and a registering slot 25 in the plate 76 at the under side of the bed. For vertically reciprocating the puncturing head 20, said head is rigid with a broad upright member 77 on the lower end of which is a roller 78 resting on the periphery 30 of a cam 79 fast on the shaft 71. The roller 78 turns on a transverse pin or screw 81 in the forked lower end of element 77. Said element has guided vertical movement between cross bars 82 rigid with the frame 35 53. The head 20 is adjustable transversely of the machine; for the purpose a screw 83 in said head extends into a transverse groove 84 in the reciprocating element 77. A retractile spring 85 is secured at one end of the 40 element 77 and at its other end to the bolt 87 or other fixed element of the machine, said spring serving to draw the head 20 downwardly below the surface of the bed 18, a slot or opening 18^a permitting the up 45 and down movements of the head 20 and its pins 20^a to produce the blind punctures a' in the strip A positioned above said head. In order that the frame 22 be raised from the bed 18 for permitting the entrance of 50 a feed strip beneath the belt 21 and thrust block 19, the frame 22 carrying the belt 21 has secured thereto, by the transverse bolt 91 hereinbefore mentioned, an L-shaped arm 88, said arm at its lower end being secured 55 also by screws 89 to the reciprocating element 77. Thus, as the cam 79 raises the head 20 the frame 22 and belt 21 will also be raised for the entrance of a strip therebeneath and upon the lowering of the puncturing head 20, the belt 21 will be lowered onto the strip to feed the same forwardly. The arm 88 extends upwardly through an opening 90 in the bed 18.

The shaft 23 of the frame 22 passes 65 through side plates 23^a inside the main side

plates 47 and bolt 23^b passing through said plates, secures the same to the side plates 47.

The shaft 25^a of roller 25 is carried by a frame 92 which presents members at the sides extending into longitudinal slots 93 70 in the sides 47 of the super-structure so that the roller 25 may be adjusted longitudinally of the machine to suit strips of different lengths.

For securing the frame 92 in adjusted position, said frame has at each side integral lugs 94 thereon which receive transverse bolts 95, the bolts being threaded right and left and engaging a turnbuckle 96, the turning of which in a proper direction will 75 loosen or tighten said bolts. Washers 97 on the bolts 95 overlap the side plates 47 to have binding engagement against the same for locking the frame 92 against movement. In order to vertically adjust the roller 25 80 for different thicknesses of strips the bearings 25^b of the shaft 25^a have rigid there-with side uprights 98 connected by a cross bar 99 to which is swiveled the lower end of a lever screw 10 but having threaded engagement with the frame 92 so that the turning of said screw will raise or lower the bearings 25^b.

Provision is made for adjusting the height of the saws 26 above the table 18 to suit 95 strips of different thicknesses. In the illustrated example at one side of the machine a bearing block 102 is provided in which saw arbor or shaft 26^a turns at one side, the reduced end of said shaft at the opposite 100 side of the machine turning in a bearing 102^a, said bearings being vertically adjustable respectively in slots 103, 104 in the opposite side plates 47. A transverse bolt 106 passes through one end of the bearing 102 105 and at the opposite end through a bearing 105 slidable in a slot 104. The bearing 102 has a lateral flange 107^b overlapping the outer surface of the adjacent side plate 47 and that nut 107 on the bolt 106 adjacent to the bearing 105 has a broad washer 107^a to bear against the adjacent side plate 47 so that the tightening or loosening of the nuts 107 will firmly hold the bearings in the adjusted position with the saws 26 at a 110 proper height above the bed.

Rigidly secured at one end to the bearing 102 by screws 108^a is a bar 108 disposed longitudinally of the machine adjacent to a side 47 and at the ends of said bar 108 120 clamps 109 are provided, consisting of elements integral with said bar 108 and at right angles thereto and separate clamp bars 109^a secured by the clamp screws 109^b. Said clamps serve to hold upstanding plates 110, 125 carrying curved guards 111, 111^a disposed respectively at the front and back of the saws 26, the one 111^a being disposed over the spring 27 controlling the exit of the strip from the machine while the other is 130

adjacent to the discharge end of the belt 24. The arrangement is such that as the strip arrives at the saws 26, the opposite end of the strip will still be beneath the roller 25 and will be held beneath said roller until the grooves a^2 are formed a proper length, the strip then passing from beneath the roller 25. As soon as the strip is thus relieved from the pressure of the roller 25, 10 the saw teeth will grip the strip and give it a quick forward movement to discharge it from the machine. The spring 27 retards the outgoing strip. The action of the saws will be to tilt the front end of the strip 15 downwardly and the rear end upwardly and the upward tilting movement will be arrested by the guard 111 which also prevents the strip from again being thrown against the saws. As the strip moves over the 20 spring 27 under the impetus imparted to it by the saws, it will move between said spring and the second guard 111^a and be guided out of the machine with reduced speed. The guards 111, 111^a are adjustable 25 vertically by reason of the clamps 109 to suit strips varying as to thickness.

Any suitable drive means may be provided for the revoluble parts, there being indicated one arrangement for the purpose comprising 30 a shaft 112 adapted to be driven by any suitable means (not shown) and having a pulley 113 from which a belt 114 runs to a pulley 115 on the saw shaft 26^a. A second belt 116 runs from a second pulley 117 on shaft 26^a to and about a pulley 118 on the shaft 25^a on roller 25, said belt 116 in practice preferably extending about a belt tightener consisting of rollers 119 in bearings 120 fitted in slots 121 in the frame 53. From a 35 second pulley 122 on the power shaft 112 runs a belt 123 to a pulley 124 on the cam shaft 71, said shaft having a second pulley 125 from which a belt 126 runs to a pulley 127 on the shaft 23 driving the belt 21.

40 With the above-described construction the pusher plate 16 for feeding the strips is timed to cause a strip to be positioned adjacent to the gage 17 and beneath the thrust block 19 as the belt 21 rises but before the puncturing pins 28^a are raised to the level of the top surface of the bed 18. After the puncturing head 20 is lowered to withdraw the pins 28^a from the strip the belt 21^a will be lowered against the strip and 45 will feed the same forward to the roller 25 so that it will pass along and over the belt 24 which moves with the strip. Upon the strip arriving at the saws it will be held a sufficient time for the grooves a^2 to be produced a sufficient length after which the saw will throw the strip out of the machine as described.

50 I would state in conclusion that while the illustrated example constitutes a practical embodiment of my invention, I do not limit

myself strictly to the mechanical details herein illustrated, since manifestly the same can be considerably varied without departure from the spirit of the invention as defined in the appended claims.

Having thus described my invention, I claim:

1. A machine of the class described, including a bed, a holder for stacked strips, a puncturing means, means to feed the strips laterally in single succession from the holder to the puncturing means, means to cause the punctured strips to travel from said puncturing means longitudinally of the machine, and saws to which said second means deliver punctured strips, said saws being positioned to cut grooves in the strip at the sides.

2. A machine for puncturing and grooving strips including puncturing means, a grooving saw distant from the puncturing means, and means to cause the punctured strips to travel to said saw, said last-mentioned means including a feed roller between the puncturing means and saw and sufficiently distant from the latter to act upon the strip while it travels a predetermined distance beneath the saw.

3. A strip puncturing and grooving machine including a bed, a vertically reciprocating puncturing device at the under side of said bed and movable through the latter to act on a strip, a grooving saw distant from the puncturing means, a vertically movable feed means above the bed adjacent to the puncturing means between the latter and the saw, means to operate the puncturing means and said feed means and timed to raise said feed means for permitting the entrance therebeneath of a strip as the puncturing device rises through the bed and to lower the feed means as the puncturing means descends, and additional feed means between the first-mentioned feed means and the saw.

4. In a machine of the class described, having a bed, a vertically reciprocating puncturing device at the under side of said bed and movable through the latter to act on a strip, a traveling belt disposed longitudinally of the machine on said bed and vertically movable to permit entrance of the strip or to frictionally engage the same for carrying it away from said puncturing device, and means to raise and lower said puncturing device and belt in unison.

5. A machine for puncturing and grooving wood strips, including a bed, a puncturing device, means to deliver strips to the puncturing device, a grooving saw disposed above the bed distant from the puncturing device, a feed roller above the bed, between the puncturing device and the saw, and means to cause the strips to move from the puncturing device to said feed roller, said

feed roller being such a distance from the saw as to act on the strip while the latter is moving a predetermined distance beneath the saw and to free the strip when it has 5 traversed said predetermined distance.

6. A machine for puncturing and grooving wood strips, including a bed, a puncturing device, means to deliver strips to the puncturing device, a grooving saw disposed 10 above the bed distant from the puncturing device, a feed roller above the bed, between the puncturing device and the saw, and means to cause the strips to move from the puncturing device to said feed roller, said 15 feed roller being such a distance from the saw as to act on the strip while the latter is moving a predetermined distance beneath the saw and to free the strip when it has traversed said predetermined distance; to- 20 gether with means to adjust said feed roller toward or from the saw to suit strips of different lengths.

7. In a machine for operating on grooved strips, a grooving saw, and means to feed 25 material to said saw, said means including a feed element such a distance from the saw as to act on the strip while it travels a pre-

determined distance beneath the saw, and to release the strip after said predetermined travel so that the saw teeth will give a dis- 30 charging movement to the strip; together with resilient means in the path of the outgoing strip to cause the strip to discharge at a reduced speed.

8. In a machine for operating on grooved strips, a grooving saw, and means to feed material to said saw, said means including a feed element such a distance from the saw as to act on the strip while it travels a predetermined distance beneath the saw, and 40 to release the strip after said predetermined travel so that the saw teeth will give a discharging movement to the strip; together with resilient means in the path of the outgoing strip to cause the strip to discharge 45 at a reduced speed; a guard at the front of the saw above the bed, to prevent the strip from being thrown against the saw, and a second guard at the back of the saw and above said resilient means a distance to permit 50 passage of the strip between said resilient means and said second-mentioned guard.

GEORGE O. P. KUNICKE.
